(57) CLAIM

The ornamental design for a shaving razor, as shown and described.

DESCRIPTION

FIG. 1 is a front perspective view of the shaving razor, showing the new design;

FIG. 2 is a front view of the shaving razor;

FIG. 3 is a rear view of the shaving razor;

FIG. 4 is a side view of the shaving razor;

FIG. 5 is another side view of the shaving razor;

FIG. 6 is a top view of the shaving razor; and,

FIG. 7 is a bottom view of the shaving razor.

The broken lines shown in the drawings illustrate portions of the shaving razor and form no part of the claimed design.
